UNITED STATES PATENT OFFICE.

HARRY EDGAR FOLTZ, OF GRANVILLE, PENNSYLVANIA.

DESIGN FOR COMBINED AUTOMOBILE TOP AND SUPPORT.

Application filed June 1, 1925. Serial No. 13,618. Term of patent 14 years.

To all whom it may concern:

Be it known that I, HARRY E. FOLTZ, a citizen of the United States, residing at Granville, in the county of Mifflin and State of Pennsylvania, have invented a certain new and ornamental Design for Combined Automobile Top and Support, as shown by the accompanying drawing, forming a part thereof.

Figure 1 shows a side elevational view of an automobile shown in dotted lines, provided with my invention, and

Figure 2 is a front elevational view thereof.

I claim:

The ornamental design for combined automobile top and support as shown.

HARRY EDGAR FOLTZ.
